UNITED STATES PATENT OFFICE

GEORGE A. THORMEYER, OF CHICAGO, ILLINOIS

COMBINATION IGNITION-LOCK SWITCH AND THEFT-ALARM SWITCH

Application filed August 8, 1927. Serial No. 211,345.

This invention is intended primarily as a safety lock for automobiles, and, as shown and described, provides locking means for the ignition system and also provides means for sounding an alarm by the continuous blowing of the automobile horn in the event that an unauthorized person attempts to tamper with the combination. Simultaneously with the sounding of the alarm, the hood will be locked, so that no opportunity will be afforded for cutting the horn wires and stopping the alarm, which can only be stopped by manual readjustment after the hood has been unlocked by a proper setting of the combination. In this way, any attempt to tamper with the combination dials will immediately sound a continuing alarm and direct attention to the unlawful effort to discover the true combination, so that the thief will have no opportunity to experiment with the dials in an effort, by repeated trial, to discover the proper combination.

The invention, in the form shown, comprises a set of three dials, each of which must be set to its proper position to establish the ignition circuit, and also to establish a circuit which will unlock the hood. If any one of the three dials is maladjusted by a thief or any other unauthorized person, such maladjustment will have the immediate effect of tripping off a circuit which controls the horn circuit, so that thereafter it will be impossible, save by lifting the hood, to open the horn circuit, and since the unlocking of the hood can only be effected by the establishment of the proper dial combination, a thief will have no opportunity, once the alarm is sounded, to proceed systematically in an effort to establish the true combination.

The invention in its mechanical aspects is designed in such a way that it may be readily secured to and incorporated into the dial board of the car in such a way as to prevent tampering with the wire leads which control the sounding of the alarm and the locking of the hood, so that the invention as a whole is one which fully meets the requirements of a safety lock of the character indicated.

In the drawings:

Figure 1 is a horizontal section looking

upwardly taken adjacent the lower wall of the case containing the combination lock unit, the plane of this section being on line 1—1 of Fig. 6;

Fig. 2 is a vertical section taken on line 2—2 of Fig. 1;

Fig. 3 is a sectional detail taken on line 3—3 of Fig. 2;

Fig. 4 is a view in perspective showing the spider plate which appears centrally in Fig. 2;

Fig. 5 is a view in perspective of the release cam;

Fig. 6 is an elevation showing the controls which are mounted at the front of the combination lock unit;

Fig. 7 is a plan view of the contact arm;

Fig. 8, which is a side elevation of the contact arm, shows its relation to the associated parts, one of which appears in section;

Fig. 9 is a perspective view of the contact arm;

Fig. 10 is a similar view of the stop arm;

Fig. 11 is a plan view of the position arm on the center post, the latter being shown in section;

Fig. 12 is a plan view of the under side of the panel board;

Fig. 13 is a vertical section through the horn and operating unit therefor;

Fig. 14 is a plan view of the upper side of the contact panel board;

Fig. 15 is a section therethrough taken on line 15—15 of Fig. 14; and

Fig. 16 is a detail in section taken on line 16—16 of Fig. 1.

The combination is contained within a housing which, as shown, comprises a front outer panel 20, a front inner panel 21, an inner partition 22 and a rear panel 23 in conjunction with side walls 24—24, a top wall 25 and a similar bottom wall, not shown, giving to the container as a whole a substantially rectangular box-like formation. In use, the housing will be inserted into the dial panel of a car with the front outer panel exposed, as in Fig. 6, although the mounting of the working parts can be otherwise arranged, if desired.

As shown, the housing provides a mount-

ing for a centrally disposed control shaft 26 and three radially disposed combination shafts 27, 28 and 29, which are provided on their front ends with adjusting knobs 30, 31 and 32, respectively. The control shaft 26 is likewise provided with a control lever 33 terminating in a pointer 34. The combination shafts are also provided with pointers 35, 36 and 37, respectively, which register 10 with arcuately arranged and numbered dial markings 38, 39 and 40. The pointer 34 is arranged in proximate relation to arcuately arranged dial markings 41, the different positions of which being inscribed with the words 15 "Release", "Dial set", "On", "Hood", or other words of appropriate signification.

Each of the combination shafts is provided with a contact arm 42, shown in perspective in Fig. 9, which contact arm terminates in a collar 43 rigidly secured to the shaft, which collar is provided with a pair of upstanding ears 44 having perforations 45 for the passage of circuit wires, presently to be described. The contact arm is further provided with an inner bore 46 and an outer bore 47, which carry contact studs 48 and 49, respectively, with the former of which is associated a spring 48^a by which this stud is pressed into proper electrical contact.

As shown in Fig. 8, the studs project from each side of the contact arm, and each stud at its outer end is threaded to receive a nut 50, which arrangement constitutes a binding post for the attachment of the circuit wires. Each of the contact arms is shouldered on its inner side at the point 51 to provide space for the mounting of a stop lug 52, each stop lug co-acting with a stop post 53 located in proximate relation to the combination shaft 40 upon which the associated stop lug is mounted so as to limit the rotation of the shaft.

The upper ends of the contact studs carry laterally projecting arms 54 to which the circuit wires are directly attached, said wires being led through the bores 45 in the ears 44. The contact arm is preferably made of bakelite or similar insulating material, and the studs 48 and 49 of brass or other conducting material, so that the circuits will 50 lead through the inner and outer contact studs which are arranged in each case to contact with arcuately extending inner and outer series of recesses 55 and 56, respectively, which are formed in the cross partition 22 55 which is of insulating material.

The arrangement is one which permits each of the combination shafts to be turned to different positions such as to bring the projecting inner ends of the contact studs into register with the inner and outer recesses, as shown in Fig. 14, and after the studs are thus brought into register with selected recesses, the shaft may be pressed inwardly to cause the studs to enter the regis-

tering recesses, which is the adjustment indicated in Figs. 1 and 8.

The lower end of each of the combination shafts, as shown in Figs. 1 and 3, is provided with an enlarged drum shaped head 57 which is aligned with a recess 58 in the base of a guide block 59, which is provided with an upstanding arm 60 and an inwardly extending lug 61 through which the shaft extends to permit its vertical reciprocation. The guide block 59 is also provided on its inner side with an upstanding lug 62 through which is entered a latch pin 63 carrying a coil spring 64, the outer end of which is secured to the latch pin and the inner end of which bears against the face of the lug 62, which arrangement tends to exert an outward thrust upon the latch pin.

When the combination shaft is pulled outwardly, the drum shaped head 57 will stand in register with the outer end of the latch pin, which will be held under spring tension, but as soon as the combination shaft is thrust inwardly, so that the head clears the end of the pin, the latter will snap outwardly, as in Fig. 3, and latch the shaft against retraction. This arrangement is common to all of the three shafts in the series.

The inner end of each of the latch pins (see Figs. 2 and 3) is provided with a slotted head 65, which engages a pin 66 entered through a slot 67 in one of the arms of a star wheel 68 carried by the centrally disposed control shaft 26 the arrangement being such that when the shaft is turned in a counterclockwise direction, as in Fig. 2, it will simultaneously retract all three of the latch pins and permit the three shafts to spring outwardly, each under the thrust of a coil spring 69, which encircles the shaft and has its outer end entered thereinto and its inner end hooked onto a post 70, the spring thus serving both to rotationally restore the shafts to the position marked "Dial set" in Fig. 6, and also to longitudinally restore the shaft to the outer position occupied when released by the latch pins.

The star wheel is loosely mounted upon the control shaft 26, so that the latter may be turned through a predetermined arc of movement without imparting rotation to the star wheel, but after such movement has been exhausted, a release finger 71, (see Fig. 5) which is rigid with the shaft, is brought into contact with an upstanding lug 72 on one of the arms of the star wheel, so that a continued rotation of the shaft will carry around the star wheel thereby drawing back the latch pins and releasing the combination shafts.

The control shaft 26 also carries a contact arm 73 provided with a spring pressed contact stud 74 terminating at its upper end in a binding post 75 which contact post is

positioned to co-act with either of two contacts 76 and 77, the former of which connects with a circuit wire 78 leading to a solenoid 79 for controlling the hood lock, and the latter—77—connects with a wire 80 leading to the ignition coil 81 for controlling the ignition.

The hood lock is best illustrated in Fig. 2. The core of the solenoid 79 is in the form of a latch pin 82 having a beveled latch head 83 which co-acts with a latch plate 84 extending inwardly from the wall of the engine hood 85 near the medial portion of the lower edge thereof. The latch head is guided by a U-shaped plate 86 which co-acts with an L-shaped plate 87 providing a space between the two plates for the reception of the latch plate. The solenoid and the plates 86 and 87 are secured to a fixed portion 88 of the frame in proximate relation to the lower edge of the hood, so that as the hood is swung down, the latch plate 84 will swing in between the spaced plates 86 and 87 and engage the latch head 83. The solenoid 79 is grounded by a wire 89.

A maladjustment of any one of the combination shafts will result in a continuous sounding of the horn, and the mechanism especially provided to secure this result will now be described. It is best illustrated in Figs. 12 and 13. A circuit wire 90 from the battery is branched to provide three branches 91, 92 and 93, respectively. Each of these branches leads to one of the three combination contact arms, making connection through the outermost connecting arm 54 with the contact stud 49 which swings in registry with the arcuate series of recesses 56. Each recess, save one in each series, is provided with a metal contact pin 94 (Fig. 15), provided with a head which rests upon a shoulder within the recess, the lower end of the pin being carried behind the partition 22, and each of the pins 94, which thus projects, will be connected with a lead of wire 95, 96 or 97, as the case may be, as indicated in Fig. 12, which leads are in turn connected with the one another through wires 98 and 99.

The branch wires 91, 92 and 93 connect respectively with the outermost contact studs 49 carried by the contact arms 42, so that when the respective arms are turned into registering position with any one of the recesses 56, and the combination shafts are depressed inwardly and latched, a contact will be established and one of the branches of the horn circuit will be closed in every case except one in each series, which represents the position in which a contact pin is omitted, such omission indicating a correct adjustment of the respective combination contact arms and the only ones in which a sounding of the horn will not occur.

The wire section 97 (Fig. 12) connects

with a horn lead 100 extending to a solenoid 101, the core 102 of which constitutes a latch pin which is surrounded by a coil spring 103 which will normally hold the latch pin core, as in Fig. 13, in projected position to engage with a beveled collar 104 on a spring actuated trip pin 105 terminating in a knob 106 permitting its retraction. These parts are housed in a box 107 secured to a suitable portion of the framing of the car, and the end 75 of the trip pin 105 aligns with a spring switch 108, to one member of which is secured a wire 109 leading to the battery, and to the other end of which is a wire 110 leading to the horn.

When the solenoid is energized, the pin 102 will be drawn back releasing the trip pin which, under spring pressure, will close the spring switch and thus close the horn circuit, which will be held closed until manually released by the retraction of the trip pin, and this will serve to continuously sound the horn 111, which in addition to the emergency circuit, above mentioned, is provided with the usual circuit wires 112 and 113 for normal 90 operation.

In addition to the horn circuit wire 90 with the branches 91, 92 and 93, the hood lock is released and the ignition circuit closed in a manner now to be described. In this 95 connection, it must be understood that in order to completely close the circuit, which controls the release of the hood lock and the closing of the ignition system, all three of the combination contact arms must be correctly set to the selected combination. Each of the inner contact studs 48 co-acts with a single contact pin 114 entered into one of the inner series of recesses, shown in Fig. 14, so that complete circuit closing contact will be 100 established only when all three of the contact 105 arms are set to the proper positions.

A circuit wire 115 leads from the battery to what may be termed the first of the series of contact arms and connects with the stud 48 110 thereon. A second lead of wire 116 leads from the single contact pin which co-acts with the first contact arm to the second contact arm, and in like manner a third lead of wire 117 leads to the third contact arm, while 115 an outgoing lead of wire 118 leads from the last of the contact pins 114 and connects with the binding post 75 on the controlling arm 73. Thus when all of the combination contact arms have been properly set to secure 120 contact with the respective contact pins 114, an unbroken circuit will be established through the combination controls and to the contact pin 74 on the arm 73, so that by proper adjustment of said arm, a contact may 125 be established either with the solenoid, which controls the release of the hood lock, or with the spark coil of the ignition system.

In order to properly center the control shaft 26 in its various positions of adjust- 120

ment, it is provided with a finger 119 which rides against an undulating spring track 120 secured to the inner face of the panel 21, and so arranged that when the pointer 34 of the control lever 33 stands opposite to one of the significantly marked positions, the finger 119 will lie in one of the undulations of the track, which thus tends to center the parts in the intended position. As shown in Fig. 1, all of the ingoing wires 90 and 114 from the battery and the outgoing wires 78, 80 and 100, all lead through a tube 121 in the rear wall of the housing at a point well beneath the hood of the car where it will be protected against tampering so long as the hood remains locked.

In use, it will be observed that any particular combination can be established by positioning the three contact pins 114, each within a selected one of the ten socket holes composing each series. Thus a great number of different combinations may be established. In view of the fact that the three contact pins are essential elements in the establishing of a complete circuit, it will, of course, be necessary to correctly position all of the dials before all of the gaps in the circuit are closed. The closing of this circuit by a correct setting of the dials will so condition the apparatus that the control lever 33 may be effectively employed either to unlock the hood, which is accomplished by turning the pointer 34 to the word "Hood", or to close the ignition circuit, which is accomplished by turning the pointer to the word "On".

In the second of these two adjustments, the control arm 73 carrying the contact pin 74 will be so set as to bring the pin 74 into register with the contact 76 which closes the hood lock circuit, and by energizing the solenoid 79, causes a retraction of the latch 83 which permits the hood to be lifted. The first adjustment of the pointer 34 completes the circuit leading to the ignition coil which permits the starting of the engine.

When the pointer 34 is positioned upon the space marked "Dial set", the parts will be properly positioned to permit the contact arms to be moved to any position required to establish the true combination, the various parts being indicated by the numerals on the dial panel. After one of the combination shafts has been turned to a selected position, it will be thrust backwardly which causes the contact studs 48 and 49 to enter the aligned socket holes, and if such holes constitute one factor in the selected combination, the setting of the shaft will close one of the gaps in the ignition and hood lock circuit and leave the horn circuit unaffected. The adjusted combination shaft will be held back by the engagement of the latch pin 63 with the enlarged head 57 of the shaft, and similar adjustments can then be made of the other combination shafts. When all are

properly adjusted, the engine can be started or the hood lifted, as occasion may require.

If, however, a thief begins to tamper with the lock, the first maladjustment of any one of the combination shafts will result in a closing of one of the branches of the horn circuits, any one of which is effective to draw back the pin 102 of the solenoid 101. This trips the switch mechanism which operates the horn circuit and continuously closes the horn circuit until the emergency horn circuit is manually opened, which can only be done by a lifting of the hood. Since a correct setting of the combination is required to unlock the hood, it is evident that the horn will continue to sound until attention is directed to the spot. In short, after a single maladjustment, the difficulty cannot be corrected, save by a discovery of the true combination with the alarm sounding during the entire interval.

Although the device has been described as operable to unlock the hood in order to secure access to the horn, which is a convenient method of preventing tampering with the horn, nevertheless, it is obvious that if the horn were housed otherwise than within the hood, or if some other type of signal or alarm mechanism were employed, the hood locking feature might be suitably utilized to prevent access being obtained to the horn or other alarm device howsoever located, the object and purpose being to prevent a discontinuance of the alarm by the cutting of wires or the disabling of the alarm apparatus wheresoever located, so that in the claims it will be understood that any suitable enclosure for the alarm mechanism which is capable of being locked or otherwise safeguarded is intended to be included.

I claim:

1. In a device of the class described, the combination of an adjustable member movable to a plurality of positions of adjustment, a member adjacent said adjustable member and provided with a row of socket holes constituting an alarm series and a row of socket holes constituting a locking series and located in register with the several positions of adjustment of the adjustable member, contact points positioned on said adjustable member to register with the respective rows of socket holes, the adjustable member being mounted to permit depression to cause the respective contact points to enter selected pairs of said socket holes in the companion series of holes, a contact point in each save one of the socket holes of the alarm series and positioned to register with a contact point on the adjustable member, and a contact point in one of the socket holes of the lock series, being the hole adjacent the blank socket hole of the alarm series.

2. In a device of the class described, the combination of an adjustable member mov-

- able to a plurality of positions of adjustment, a member adjacent said adjustable member and provided with a row of socket holes constituting the alarm series and a row of socket holes constituting the locking series and located in register with the several positions of adjustment of the adjustable member, contact points positioned on said adjustable member to register with the respective rows of socket holes, the adjustable member being mounted to permit depression to cause the respective contact points to enter selected pairs of said socket holes in the companion series of holes, removable contact points one in each save one 15 of the socket holes of the alarm series and positioned to register with a contact point on the adjustable member, and a removable contact point in one of the socket holes of the locking series, being the hole adjacent the blank socket 20 hole of the alarm series.
3. In a device of the class described, a rotatable combination arm provided with two contact studs, a member adjacent said arm and provided with an alarm series of arcuately arranged socket holes adapted each to receive a contact stud of the combination arm and further provided with a locking series of arcuately arranged socket holes adapted each to receive the other contact stud on the 25 combination arm, a series of contact points located one within each save one of the socket holes of the alarm series, and a single contact point located within that one of the locking series of socket holes which lies adjacent the unoccupied socket hole of the alarm series, the combination arm being depressible to bring the contact studs into engagement with the contact points in the socket holes.
4. In a device of the class described, a rotatable combination arm provided with two contact studs, a member adjacent said arm and provided with an alarm series of arcuately arranged socket holes adapted each to receive one contact stud of the combination arm and further provided with a locking series of arcuately arranged socket holes adapted each to receive the other contact stud on the combination arm, a series of removable alarm contact points located one within each save one of the 45 socket holes of the alarm series, and a single removable contact point located within that one of the locking series of socket holes which lies adjacent the unoccupied socket hole of the alarm series, the combination arm being depressible to bring the contact studs into engagement with the contact points in the socket holes.
5. In a device of the class described, a plurality of rotatable combination arms each provided with two contact studs, a member adjacent said arms and provided with a plurality of alarm series of arcuately arranged socket holes adapted each to receive one contact stud of a combination arm and further provided with a plurality of locking 60
- series of arcuate arranged socket holes adapted each to receive the other contact stud on a combination arm, a series of contact points located one within each save one of the socket holes of the alarm series, a single contact point located within that one of the locking series of socket holes which lies adjacent the unoccupied socket hole of the alarm series, the combination arms being depressible to bring the contact studs into engagement with the contact points in the socket holes, and an adjustable controlling arm provided with a contact adapted to co-act in closing circuits with the contact studs of the combination arms and also to be thrown to a non-operative position.
6. In a device of the class described, a plurality of adjustable combination arms each provided with two contact studs, a fixed member associated with said arms and provided with a plurality of alarm series of recesses and a plurality of locking series of recesses, said series being disposed to permit depression of the contact studs into selected recesses in the companion series, a contact point in each save one of the recesses of each alarm series, a single contact point in each locking series and disposed in that recess which aligns with the unoccupied recess of the associated alarm series, a rotatable shaft for each combination arm, said shafts being also longitudinally adjustable to cause the contact studs to enter the recesses, latch mechanism for each of the shafts for holding the same in depressed position, means for simultaneously withdrawing each of the latches, a rotatable control shaft upon which said latch withdrawing means is mounted, a contact arm carried by said control shaft and provided with a circuit closing contact stud, and a pair of contacts positioned to be engaged by the contact stud on the controlling contact arm in two of its positions of adjustment.
7. In a device of the class described, a plurality of adjustable combination arms each provided with two contact studs, a fixed member associated with said arms and provided with a plurality of alarm series of recesses and a plurality of locking series of recesses, said series being disposed to permit depression of the contact studs into selected recesses in the companion series, contact point in each save one of the recesses of each alarm series, a single contact point in each locking series and disposed in that recess which aligns with the unoccupied recess of the associated alarm series, a rotatable shaft for each combination arm, said shafts being also longitudinally adjustable to cause the contact studs to enter the recesses and spring pressed in the opposite direction, latch mechanism for each of the shafts for holding the same in depressed position, means for simultaneously withdrawing each of the 110 115 120 125 130

latches, a rotatable control shaft upon which said latch withdrawing means is mounted, a contact arm carried by said control shaft and provided with a circuit closing contact stud, and a pair of contacts positioned to be engaged by the contact stud on the controlling contact arm in two of its positions of adjustment.

8. In a device of the class described, a plurality of adjustable combination arms each provided with two contact studs, a fixed member associated with said arms and provided with a plurality of alarm series of recesses and a plurality of locking series of recesses, said series being disposed to permit depression of the contact studs into selected recesses in the companion series, a contact point in each save one of the recesses of each alarm device, a single contact point in each locking series and disposed in that recess which aligns with the unoccupied recess of the associated alarm series, a rotatable shaft for each combination arm, said shafts being also longitudinally adjustable to cause the contact studs to enter the recesses and spring pressed in the opposite direction, independently depressible latch mechanism for each of the shafts for independently holding the same in depressed position, means for simultaneously withdrawing each of the latches, a rotatable control shaft upon which said latch withdrawing means is mounted, a contact arm carried by said control shaft and provided with a circuit closing contact stud, and a pair of contacts positioned to be engaged by the contact stud on the controlling contact arm in two of its positions of adjustment.

GEORGE A. THORMEYER.
